UNITED STATES PATENT OFFICE.

MAXWELL C. LANG, OF INDIANAPOLIS, INDIANA.

DESIGN FOR A FINGER RING.

Application filed December 30, 1927. Serial No. 24,699. Term of patent 3½ years.

To all whom it may concern:

Be it known that MAXWELL C. LANG, a citizen of the United States, residing at Indianapolis, in the county of Marion and State of Indiana, has invented a certain new, original, and ornamental Design for a Finger Ring, of which the following is a specification, reference being had to the accompanying drawing, forming a part thereof.

Fig. 1, is an edge elevation of a finger ring on an enlarged scale, showing my new design; and

Fig. 2, is a side elevation of the ring on the same enlarged scale.

The dotted lines at the top of the ring in both Figs. 1 and 2 indicate a stone setting.

I claim:

The ornamental design for a finger ring, as shown and described.

In testimony whereof I affix my signature.

MAXWELL C. LANG.
